UNITED STATES PATENT OFFICE.

JOHN N. RENFRO, OF EBENEZER, MISSOURI, ASSIGNOR OF ONE-HALF TO
JOHN A. HEADLEE, OF SAME PLACE.

CHURN.

SPECIFICATION forming part of Letters Patent No. 282,224, dated July 31, 1883.

Application filed April 17, 1883. (No model.)

To all whom it may concern:

Be it known that I, JOHN N. RENFRO, of Ebenezer, in the county of Greene and State of Missouri, have invented certain new and useful Improvements in Churns; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved churn-dasher. Fig. 2 is a longitudinal sectional view through the frame of the same. Fig. 3 is a cross-section through line *xx* in Fig. 2; and Fig. 4 is a detail view of the top part of the frame, showing the manner of securing the dasher-staff in position.

Similar letters of reference indicate corresponding parts in all the figures.

My invention has relation to rotary churn-dashers; and it consists in the improved construction and combination of parts of the same, which will be hereinafter more fully described and claimed.

In the accompanying drawings, A is the top, and B the bottom, piece of the dasher-frame, which are connected by the side pieces, C C. The latter are enlarged across the middle, as shown at D, forming a swelled portion, the swell of which gradually increases from opposite ends of the side piece. This swelled portion has a series of perforations or apertures, d, and is provided with a recess, E, adapted to receive a spring, e, which, by bearing against the inner wall of the churn or cream-receptacle, into which the frame is inserted, will hold the latter firmly in place during the operation of churning. If desired, however, the cream-receptacle may be provided with parallel cleats, adapted to hold the frame in place by slipping this into the ways formed by the cleats in a well-understood manner. In either case it will be seen that the frame can be readily removed from the cream-receptacle whenever desired for cleaning or for other purposes.

F is the dasher-staff, which works in a box or recess, b, in the lower cross-piece, B, and rests with its upper end in a notch, G, cut in

one side of the top piece, A. The staff is locked in position in its top bearing, G, by means of the latch-piece H, which is held in place removably upon the top piece, A, by means of the pins h h. Thus, by removing one of these pins the latch-piece H can be swung to one side, as indicated in Fig. 4 of the drawings, when the dasher-staff with its dasher can readily be removed from the frame, and this, it will be seen, may be done without removing frame A B C from the churn. Upon that part of the dasher-staff which works in the frame are secured the cross-heads I and K at right angles to each other, the outer ends of which are connected by strips L, curved, as clearly shown in Fig. 1 of the drawings, into an elongated S-shape, so as to conform to the swell or curvature of the side pieces, C C. Each of these curved strips L is bent at right angles along its outer edge to form a flange, M, which, in operating the device, will cut the cream, and thus cause the butter to "come" much more rapidly than where the cream is simply being stirred or agitated by the rotary dasher. These flanges M are bent in opposite directions, as will appear more clearly by reference to Fig. 3 in the drawings, the dasher being rotated in the direction of the arrows shown in that figure. Each of the curved strips L is provided with a row or series of apertures 80 (shown at l) for the better agitation of the cream.

From the foregoing description, taken in connection with the drawing, the operation of my improved rotary churn-dasher will readily be understood without requiring further explanation.

The dasher-staff F may be rotated by any suitable gearing or other mechanism, when the dasher, comprised of the parts I, K, and L 90 L, operating in conjunction with the swelled and perforated side pieces, C C, will agitate and cut the cream in all parts of the churn, so as to cause the butter to come with great rapidity. After the butter has been formed 95 it may be removed from the churn without removing the dasher-frame simply by unlatching the latch-piece H and slipping the dasher-staff with the dasher out of its bearings G and b.

Having thus described my invention, I claim and desire to secure by Letters Patent of the United States—

- 5 1. The combination of the frame composed of the top piece, A, having notch G, bottom piece, B, having bearing b, and side pieces, C C, having swelled middle parts, D, provided with perforations d, removable latch-piece H, pins h h, and dasher consisting of the staff F, top and bottom cross-heads, I and K, curved connecting-strips L, having perforations l, and flanges M, all constructed and combined to operate substantially in the manner and for the purpose herein shown and set forth.
- 10 15 2. The combination of the frame composed of the top piece, A, having notch G, bottom piece, B, having bearing b, and side pieces, C C, having swelled middle parts, D, provided

with perforations d, and with recesses E, having springs e, adapted to hold the frame in position in the cream-receptacle by friction, removable latch-piece H, pins h h, and dasher consisting of the staff F, top and bottom cross-heads, I and K, curved connecting-strips L, having perforations l, and flanges M, all constructed and combined to operate substantially in the manner and for the purpose herein shown and specified.

In testimony that I claim the foregoing as my own I have hereunto affixed my signature in presence of two witnesses.

JOHN N. RENFRO.
